HAIR THINNING MECHANISM

Mathew Andis, Racine, Wis.

Application June 22, 1933, Serial No. 677,068

2 Claims. (Cl. 30—1)

My invention relates to improvements in hair thinning mechanisms.

The primary object of my invention is to provide a hair thinning mechanism which may be drawn through hair with a combing action and a predetermined portion of the hair cut progressively as the tool is being advanced, the hairs being preferably cut individually or in exceedingly small groups of two or three hairs to be cut in 10 any single operation of a shearing tooth as distinguished from the cutting of hair in clusters or locks, as is usually done when trimming out surplus hair with ordinary shears.

More particularly stated, objects of my invention are to provide successful means for the removal of hair uniformly and in definite proportions while moving the cutters at substantially uniform speed in combing operations; to provide a power driven hair thinning mechanism 15 similar in its general construction to an ordinary hair clipper but with a shearing comb plate and vibratory cutter blade which have been modified to adapt them for cutting a desired proportion of the hair, leaving the remainder uncut during 20 any given combing movement of the comb plate and cutter blade teeth through the hair; to provide a shearing comb plate with combing teeth which are relatively long and thin as compared with those of an ordinary hair clipper, and the 25 extremities of which are adapted to be moved along the scalp in the same manner as the teeth of an ordinary comb, said teeth being also provided with narrow bearing faces adjacent the extremities of the teeth, the side margins of 30 which faces form shearing edges for cooperation with the shearing teeth of the cutters; to provide vibratory cutter plates or blades having correspondingly thin teeth and substantially point-bearing shearing projections for cooperation 35 with the shearing faces of the comb plate teeth, each along a line but little, if any, longer than the diameter of an individual hair of average coarseness; to provide such a hair thinning mechanism with power driven means for vibrating the 40 cutter plate or blade at a substantially predetermined speed, whereby an operator may accurately predetermine the quantity of hair to be removed by regulating and keeping uniform the rate of advancement of the comb; and in general to provide effective mechanisms for performing substantially uniform thinning operations in such a manner as to keep the results of such operations invisible under all subsequent combing 45 conditions.

55 In the drawing:

Figure 1 is a side elevation of my improved mechanism as it appears in operation.

Figure 2 is an enlarged view of the working or shearing end of the tool showing the shearing comb plate, cutter blade, and associated parts 5 in section on a plane extending between the shearing teeth.

Figure 3 is a perspective view of the vibratory cutter blade.

Figure 4 is a perspective view of the shearing 10 comb plate.

Figure 5 is an enlarged fragmentary view of a pair of cooperative shearing teeth on the shearing comb plate and cutter blade respectively, and illustrating the manner in which an individual 15 hair may be cut without severing those adjacent thereto.

Figure 6 is a fragmentary enlarged plan view of the cutter blade as viewed from the inner side, i. e., the side opposing the shearing comb plate 20 when the parts are assembled, a portion of the shearing comb plate being also illustrated in assembled relation to the cutter blade.

Like parts are identified by the same reference characters throughout the several views. 25

The handle 10 is similar to that of an ordinary hair clipper of a type in common use. This handle may be assumed to house an electrical motor of either the electromagnetic vibratory type or a rotary motor, receiving current through 30 the conductors 11. The type of motor is immaterial to the invention herein claimed, and it is therefore not illustrated. In accordance with ordinary practice, it may be assumed to be capable of laterally reciprocating a lever or vibratory 35 arm 12 having a forked extremity in pressure engagement with a pair of lugs 13 attached to a vibratory cutter blade 14. This form of connection for applying power to vibrate the cutter blade being well known, further illustration and 40 description are deemed unnecessary.

The teeth 15 of the cutter blade are preferably relatively long and thin as compared with those of an ordinary vibratory cutter blade for a hair clipper. As best shown in Figure 6, the spaces 45 between the teeth are of a width several times that of the teeth themselves, and as best shown in Figure 5, each tooth has a shearing projection 17 substantially at its extremity and preferably in a central plane of the tooth transverse to the 50 upper and lower faces of the blade. This projection extends in the direction of the shearing comb plate teeth and is tapered for an approximately point-bearing contact therewith, although the end of the projection is flat over a small area 55

and has a shearing side margin 18, as best shown in Figure 6, which preferably has a length of approximately .010 to .015 of an inch.

These projections 17 not only have shearing margins 18, but their form is such as to adapt them for service as laterally moving comb teeth adapted to select individual hairs for shearing purposes while deflecting adjacent hair forwardly and rearwardly in the spaces between the comb teeth 24, whereby the deflected hair may be flexed over the bearing surfaces 26 of the teeth 24 without severance. In the rear of these bearing surfaces 26 both sets of teeth are provided with transversely extending clearance recesses 15 within which the hair will not be severed.

But in order to obtain selection of individual hairs for severance it is important to employ laterally moving comb teeth 17 which engage only a minute fraction of the bearing surfaces 26, for if the dimensions of the bearing surfaces 26 were reduced in length as measured from the points of the teeth 24 rearwardly to correspond with the dimensions of the shearing projections 17, but little hair would be cut, since practically all of it would then be deflected from the extremely limited shearing zone. By making the bearing surfaces 26 of substantial length and having the shearing projections 17 engage these surfaces at a substantial distance to the rear of the front and rear ends of the bearing surfaces 26, a sufficient number of uncut hairs will be in engagement with the bearing surfaces 26 to hold each individual hair from shifting toward the front or rear when directly engaged by a projection 17.

The shearing comb plate 20 is secured to the heel 21 of the casing or handle 10, preferably by screws 22. This shearing comb plate is similar to that of an ordinary hair clipper with the exception that its teeth 24 are comparatively long and thin and are widely spaced from each other as above described with reference to the teeth of the vibratory cutter blade. Near their outer ends the margins of the teeth 24 which oppose the shearing projections 17 have elongated bearing surfaces 26, the side margins of which are adapted to serve as shearing margins in cooperation with the shearing margins of the projections 17 on the cutter blade teeth.

While an ordinary hair clipper is usually pushed along the scalp with the cutter teeth operating in advance of the body of the comb plate, my improved hair thinning mechanism is reversed in position as indicated in Figure 1, whereby the teeth of the comb plate may be drawn through the hair with an ordinary combing action. No other function will be performed unless the cutter blade is vibrated.

By applying power to vibrate the cutter blade transversely of the line of movement of the comb, i. e., through the medium of the actuating arm 12 in a power driven mechanism, the individual hairs will be engaged between the shearing projections 17 and the shearing margin of the bearing faces 26 of the shearing comb plate teeth and severed without severing other hair at either side thereof.

Preferably the reciprocations of the vibratory cutter blade will be short and the relation of the teeth of said blade to the shearing comb plate teeth may be such that movement of the cutter blade in one direction will carry each of its teeth partially across the spaces between the vibratory comb plate teeth, and the movement in the other

direction may be only sufficient to carry the shearing projections 17 only partially across the bearing surfaces 26 of the associated shearing comb plate teeth.

However, the vibratory movement may be such as to carry each cutter blade tooth entirely across its associated comb plate tooth, in which event cutting will take place on both sides.

While I preferably form the projections 17 with such narrow extremities that only one hair will be engaged at a time by any given projection, it will, of course, be understood that by varying the length of the shearing edge 18 in the manufacture of the teeth, the number of individual hairs to be selected from among others and cut in a single stroke by a single tooth of the vibratory cutter blade may be correspondingly varied. The selection and cutting of one, two or three, or even more, hairs by any single tooth may be regarded as individual selection and cutting within the meaning hereof, as distinguished from the cutting of locks of hair in a manner to leave substantial gaps in the uncut hair such as may be visible unless the remaining hair is combed across such gaps.

I prefer to predetermine the degree of convergence of the front and rear faces of the projections 17 with reference to the desired length of the shearing edge. Thus, these projections may have adequate strength at their junction with the body portions of the teeth regardless of the extent to which they are tapered.

While it would be possible to fixedly mount the blade 14 upon the handle or casing 10 and apply the power to vibrate the comb plate 20, I prefer to vibrate the blade 14 in order to avoid the discomfort that would result from a vibration of the teeth 24 in contact with the scalp, and in order to avoid the resistance and additional load that would thus be imposed upon the motor.

I claim:

1. A hair thinning mechanism, including the combination of a comb plate and a vibratory cutter blade each having teeth provided with rounded ends, and mutually contacting surfaces having shearing side margins extending rearwardly from said rounded ends, the teeth of the respective plates being spaced from each other at all other points and those of the cutter blade having their bearing portions formed upon the extremities of projections having convergent front and rear walls adapted to move with a vibratory combing action to separate individual hairs to be sheared whereby the hair to be cut may be substantially individualized and sheared in power driven vibrations of high frequency.

2. A hair thinning mechanism including the combination with a comb plate having teeth provided with rounded ends and shearing side margins extending rearwardly from the inwardly curving surfaces of said rounded ends, and a vibratory cutter blade having teeth provided with rounded ends and adjacent said ends having spacing projections extending into bearing contact with the portions of the comb teeth having said shearing margins, said spacing projections having shearing side margins of a length substantially corresponding to the diameter of an individual hair of maximum size and the teeth of the cutter blade being otherwise held by said spacing projections out of contact with the comb teeth.

MATHEW ANDIS.
